To all whom it may concern:

Be it known that I, ARCHIBALD F. 5. The design of my invention may be applied to or wrought in Brussels, Wilton, velvet, or other carpeting in such colors or combinations of colors as may be desired; and I do hereby declare that the drawing accompanying this specification presents to the eye of the observer a clear understanding of my new and original design sufficient to enable such person to ascertain its leading characteristic or essential feature or features.

o. In the drawing, A is the body, B the border, and A and B the complete carpet. However, for the sake of a further description

the leading or characteristic feature of my design may be said to be the ornamental thing *a* and floral sprays *b* disposed on opposite 25 sides thereof, so as to form a wreath-like figure, and displayed upon a background *c*.

What I claim as new, and desire to secure by Letters Patent, is—

1. In the design for a carpet the body A, substantially as shown. 30
2. In a design for a carpet the border B, substantially as shown.
3. The design for a carpet consisting of the body A, and the border B, substantially as 35 shown.

In testimony whereof I have hereunto signed my name in the presence of two witnesses.
